FIG. 3 is an enlarged top-front-left perspective view of the annotated portion of FIG. 2.

FIG. 4 is a top-front-right perspective view of the brachytherapy applicator.

FIG. 5 is an annotated top-front-right perspective view of the brachytherapy applicator shown in FIG. 4.

FIG. 6 is an enlarged top-front-right perspective view of the annotated portion of FIG. 5.

FIG. 7 is a top-rear-right perspective view of the brachytherapy applicator.

(Continued)

FIG. 8 is an annotated top-rear-right perspective view of the brachytherapy applicator shown in FIG. 7.

FIG. 9 is an enlarged top-rear-right perspective view of the annotated portion of FIG. 8.

FIG. 10 is a top-rear-left perspective view of the brachytherapy applicator.

FIG. 11 is an annotated top-rear-left perspective view of the brachytherapy applicator shown in FIG. 10.

FIG. 12 is an enlarged top-rear-left perspective view of the annotated portion of FIG. 11.

FIG. 13 is a bottom-front-right perspective view of the brachytherapy applicator.

FIG. 14 is an annotated bottom-front-right perspective view of the brachytherapy applicator shown in FIG. 13.

FIG. 15 is an enlarged bottom-front-right perspective view of the annotated portion of FIG. 14.

FIG. 16 is a bottom-front-left perspective view of the brachytherapy applicator.

FIG. 17 is an annotated bottom-front-left perspective view of the brachytherapy applicator shown in FIG. 16.

FIG. 18 is an enlarged bottom-front-left perspective view of the annotated portion of FIG. 17.

FIG. 19 is a bottom-rear-left perspective view of the brachytherapy applicator.

FIG. 20 is an annotated bottom-rear-left perspective view of the brachytherapy applicator shown in FIG. 19.

FIG. 21 is an enlarged bottom-rear-left perspective view of the annotated portion of FIG. 20.

FIG. 22 is a bottom-rear-right perspective view of the brachytherapy applicator.

FIG. 23 is an annotated bottom-rear-right perspective view of the brachytherapy applicator shown in FIG. 22.

FIG. 24 is an enlarged bottom-rear-right perspective view of the annotated portion of FIG. 23.

FIG. 25 is a right side view of the brachytherapy applicator.

FIG. 26 is an annotated right side view of the brachytherapy applicator shown in FIG. 25.

FIG. 27 is an enlarged right side view of the annotated portion of FIG. 26.

FIG. 28 is a left side view of the brachytherapy applicator.

FIG. 29 is an annotated left side view of the brachytherapy applicator shown in FIG. 28.

FIG. 30 is an enlarged left side view of the annotated portion of FIG. 29.

FIG. 31 is a rear view of the brachytherapy applicator.

FIG. 32 is a front view of the brachytherapy applicator.

FIG. 33 is a top view of the brachytherapy applicator.

FIG. 34 is an annotated top view of the brachytherapy applicator shown in FIG. 33.

FIG. 35 is an enlarged top view of the annotated portion of FIG. 34.

FIG. 36 is a bottom view of the brachytherapy applicator.

FIG. 37 is an annotated bottom view of the brachytherapy applicator shown in FIG. 36; and,

FIG. 38 is an enlarged bottom view of the annotated portion of FIG. 37.

The word "Elekta" with its associated icon forming part of the claimed design is a registered trademark of Elekta AB. The short-dash long-dash lines shown in the drawings depict boundaries of the enlarged view indicators and form no parts

of the claimed design. The dash-dash broken lines depict unclaimed portions of the brachytherapy applicator and form no parts of the claimed design.
